UNITED STATES PATENT OFFICE.

WAVERLEY G. HORTON, OF CHICAGO, ILLINOIS.

GOLF-CLUB HEAD.

1,361,258.

Specification of Letters Patent.

Patented Dec. 7, 1920.

Application filed March 21, 1919. Serial No. 284,041.

To all whom it may concern:

Be it known that I, W.AVERLEY G. HORTON, a citizen of the United States, residing at Chicago, in the county of Cook and State 5 of Illinois, have invented certain new and useful Improvements in Golf-Club Heads, of which the following is a description.

My invention belongs to that general class of golf clubs usually termed "wooden clubs," 10 ordinarily comprising what is termed the "driver," the "brassy," the "spoon," etc. Such clubs as distinguished from the metal clubs, consist of a comparatively broad sole, which as the club is poised rests upon or 15 above the turf substantially parallel therewith. When the heads are properly balanced, clubs of this character are readily manipulated with a broad sweep forward, during which the face of the club contacts 20 with the ball, lifting the ball and securing comparatively great distance, resiliency between the club head and the ball aiding in securing this result. Such clubs are usually employed for what may be termed "distance" 25 purposes. In view of the broad sweep and the force with which such clubs are swung, as well as the peculiar poise of the shaft in the hand of the player, the proper balance of the head has much to do 30 not only with the distance gained, but the accuracy secured. If the face of the club tends to tilt downward, the ball will be driven downward upon the turf, and neither 35 distance nor accuracy gained. Upon the other hand, if the rear of the head of the club is tilted downward too much, it may result either in topping the ball, with but a slight distance gained, or the ball may be lofted, with a similar result. Further difficulties are encountered if either the toe or 40 heel of the club is advanced too much, resulting in either driving the ball in an improper direction, or in what is termed "slicing" or "pulling."

My improved club head is designed to secure advantages in the direction mentioned, while at the same time producing a club at a reasonable price and of great durability. To this end my invention consists in the 45 novel construction, arrangement and combination of parts herein shown and described, and more particularly pointed out in the claims.

In the drawings, wherein like reference

characters indicate like or corresponding parts,—

Figure 1 is a top plan view of my improved club head;

Fig. 2 is a front face view of the same;

Fig. 3 is a rear edge view of the same;

Fig. 4 is a section on substantially the line 4—4 of Fig. 2;

Fig. 5 is a section on substantially the line 5—5 of Fig. 2;

Fig. 6 is a rear view of the metal portion of my improved club head;

Fig. 7 is a perspective view of the body part of the head; and

Fig. 8 illustrates a slightly modified form of metal part for the head.

In the drawings, 1 represents a metal part adapted to be mounted upon the usual shaft 2, said metal part comprising the sole 3, the neck 4, the heel 5 and the toe 6 of the club. A web 7 on the upper face of the club extends from the neck 4 to the toe 6. The metal part as thus constructed constitutes an integral casing preferably wider at the face than at the rear opening, within which casing a body 8 of suitable material snugly fits 70 and is securely held in position in any preferred manner. As shown, screws 9, extending through the web part of the body, aided by a similar screw 10 through the toe, the screw 11 through the heel, and one or more 75 screws through the sole (not shown), serve to aid in firmly retaining the body in position within the casing. Any suitable cementitious material may also be employed if desired. In the preferred construction, the 80 sole extends to the face in line with the front face of the body 8 and forms a part of said face, as shown in Fig. 4, while the web 7 is set back from the face of the club, as indicated at 12. In the preferred construction, the 85 sole on its interior or upper face, is also formed with a shoulder 17 or equivalent part. The body part is provided with a shoulder as at 13, thus securing a shouldered engagement between the body and the web 100 at that point, while a similar engagement is provided at 17 on the sole. The rear or back portion of the body may be weighted in the usual manner as at 14.

Some players prefer that the face of the 105 club be provided with an insert of different material from the body of the club for the purpose of gaining increased resiliency or

greater driving effect. Such an insert may be readily employed in my improved club head by inserting an insert 15 in the face of the body, extending backward into the head 5 the desired distance. The insert may be maintained in position in any desired manner and may be of any desired contour upon the face of the club.

In Fig. 8 a similar construction is shown, 10 with the exception that the metal portion is separated at the toe, gaining slightly in convenience in assembling the body within the metal part, while the various screw connections mentioned are ordinarily sufficient to 15 secure the desired rigid connection between the parts. The integral metal part, however, as shown in Figs. 1 to 6, is preferred.

The body part of the club may be of such material as is desired. It is generally of 20 some form of hard wood, although when employed with a metal retaining casing, as in my invention, other materials may be employed, hence I do not desire to limit myself to the particular material employed. I 25 have secured satisfactory results by constructing the casing of aluminum or similar material, and the body of wood, with an insert of ivory or gutta-percha or similar material.

30 By my improved means of manufacturing the club head, it may be precisely and exactly balanced as desired. While in assembling, the same casing may be employed with any body desired to produce the particular type of club wanted, such as driver, brassy, spoon, etc., the club may be fashioned as desired also, a wide range being provided as shown. The sole extends rearward from the face, securing the most ap- 35 proved form of construction in that particular, while the over-balancing of the club toward the front is overcome by setting the web 7 back from the front a sufficient distance and truing the balance by the weight 40 14, or equivalent means. The balance of the club in a longitudinal direction is easily secured by the thickness of the metal at the toe and heel. The neck is preferably well cut back as at 16, which aids materially in as- 45 sembling the parts, secures a longer face if desired, and aids in the longitudinal balance of the head.

Having thus described my invention, it is 50 obvious that various immaterial modifications may be made in the same without departing from the spirit of my invention;

hence I do not wish to be understood as limiting myself to the exact form, construction, arrangement and combination of parts herein shown and described, or uses men- 60 tioned.

What I claim as new and desire to secure by Letters Patent is:

1. A club head comprising a casing adapt- 65 ed to be mounted on the shaft, and forming the sole, neck, heel and toe of the club, with an upper web extending from the neck to the toe, the front edge of the web being set back from the front edge of the sole, in combination with a coöperating body of 70 suitable material snugly fitted in the casing and secured thereto, with the front face in line with the front edge of the sole, and on its upper face in shouldered engagement with the front edge of the web. 75

2. A club head comprising a casing adapt- 80 ed to be mounted upon the shaft, and forming the sole, neck, heel and toe of the club, with a web on the upper face extending from the neck to the toe with the front edge of the web set back from the front edge of the sole, the sole on its inner face provided with a shoulder extending longitudinally thereof, in combination with a coöperating body of suitable material snugly fitted in the 85 casing and secured thereto, with the front face in line with the front edge of the sole, its lower face in shouldered contact with the shoulder on the sole, and its upper face in shouldered contact with the front edge of 90 the web.

3. A golf club head comprising a metal casing adapted to be mounted on the shaft, and forming the sole, neck, heel and toe of the club, with a web on the upper face ex- 95 tending from the neck to the toe, the front edge of the web being set back from the front edge of the sole, in combination with a coöperating body part of suitable material snugly fitted in the metal part and se- 100 cured thereto, with the front face in line with the front edge of the sole, and on its upper face in shouldered engagement with the front edge of the web, and an insert mounted in the face edge of the body. 105

In testimony whereof, I have hereunto signed my name in the presence of two sub- 110 scribing witnesses.

WAVERLEY G. HORTON.
